UNITED STATES PATENT OFFICE.

CLINTON H. LEGGETT, OF ELIZABETH, NEW JERSEY.

DESIGN FOR A MATCH-STAND.

Specification forming part of Design No. 6,285, dated December 10, 1872.

To all whom it may concern:

Be it known that I, CLINTON H. LEGGETT, of Elizabeth, in the county of Union and State of New Jersey, have invented a new Design for a Match-Stand, of which the following is a specification:

Nature of the design.

The nature of my design is fully represented in the accompanying drawing, to which reference is made.

A represents a match-box cast in one piece except the cover, the sides and ends being corrugated to give an ornamental appearance, and the exterior bottom being cast with a rough frictional surface to ignite the match

upon. The cover has radial corrugations cast thereon, and has projecting pins cast thereto, which make the hinge-joint. The receptacle B for burnt matches is cast in the shape of a scalloped shell, and the box A and receptacle B are united to a back, C, in any proper manner.

Claim.

I claim—

The design for a match-stand, substantially as shown and described in the accompanying drawing and specification.

CLINTON H. LEGGETT.
